US00D766862S

(12) **United States Design Patent** (10) **Patent No.:** **US D766,862 S**
(45) **Date of Patent:** **** Sep. 20, 2016**

(54) **MOBILE PHONE**

(71) Applicant: **LG ELECTRONICS INC.**, Seoul (KR)

(72) Inventors: **Soon Hyun Park**, Seoul (KR); **Sei Hyun Cho**, Seoul (KR); **Sang Hyuck Lee**, Seoul (KR)

(73) Assignee: **LG Electronics Inc.**, Seoul (KR)

(**) Term: **14 Years**

(21) Appl. No.: **29/504,826**

(22) Filed: **Oct. 9, 2014**

(30) **Foreign Application Priority Data**

Apr. 22, 2014 (KR) 30-2014-0020393

(51) **LOC (10) Cl.** **14-03**

(57) **CLAIM**

We claim the ornamental design for a mobile phone, as shown and described.

DESCRIPTION

FIG. 1 is a perspective view of a mobile phone showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view in an exploded state; and,

FIG. 9 is a right-side elevation view in an exploded state. The broken lines that are immediately adjacent to the claim, and define unshaded regions, represent the bounds of the claim while all other broken lines are directed to environment; the broken lines form no part of the claimed design.

1 Claim, 6 Drawing Sheets
